[57] ABSTRACT

A sound-attenuating structure includes a non-absorbing shell and a mat of sound-absorbing material held parallel to and spaced from the shell a distance equal to one-quarter the wave length of the highest frequency to be attenuated. The thickness of the mat of sound-absorbing material is defined by the expression:

$$d = [c(f_2 - f_1)] / 4 \cdot f_1 \cdot f_2$$

where c is the propagation speed of sound in the atmosphere, f_2 is the highest, and f_1 the lowest acoustic frequency to be attenuated.

FIG. 4

SOUND ATTENUATING STRUCTURE

BACKGROUND OF THE INVENTION

This invention relates in general to sound-attenuating structures, and in particular, to an application in the automobile industry as a sound-attenuating fire wall between the engine and passenger compartments, and also as a fluid conduit such as an exhaust pipe.

In known sound-attenuating arrangements, it is a common expedient to apply a sound-absorbing material to a non-absorbing supporting shell such as a sheet metal partition. While this technique may indeed achieve the desired sound attenuation, provided the sound-absorbing layer is thick enough, it is a wasteful technique because a substantial proportion of the sound-absorbing material contributes nothing to the desired sound-attenuating effect but merely adds size, weight and cost to the final product. What the art lacks and has long sought is a sound-attenuating structure which uses the sound-absorbent material at maximum efficiency so that the size, weight and cost of the final product is minimized.

SUMMARY OF THE INVENTION

Accordingly, there is provided, according to one embodiment of this invention, a sound-absorbing wall having a non-absorbing shell and a sound-absorbing mat spaced from the non-absorbing shell a distance equal to one-quarter of the wave length of the highest frequency to be attenuated.

Another embodiment of the invention is a fluid conduit in which the non-absorbing shell forms the exterior casing of the conduit, and the spaced sound-absorbing mat is disposed interiorly of the shell and concentrically therewith, leaving an interspatial zone between the shell and the mat for flow of fluid.

To achieve maximum efficiency, the thickness d of the mat of absorbent material may be calculated by the following relationship:

$$d = [c(f_2 - f_1)]/4f_1f_2$$

where c equals the sound propagation velocity in the atmosphere and f_2 and f_1 equal the highest and lowest frequencies to be attenuated, respectively.

DESCRIPTION OF THE DRAWINGS

For a better understanding of the invention, reference may be had to the following description of a preferred embodiment, read in conjunction with the figures of the accompanying drawings, in which:

FIG. 1 is a cross section of a portion of a curved sound-absorbing wall constructed according to this invention;

FIG. 2 is a graph in the solid curve showing the percentage of sound absorption at various frequencies for a given thickness of sound-absorbing material applied directly to a non-absorbent shell, and showing, in the broken curve, the corresponding percentage of sound absorption with the same thickness of absorbent material spaced from the non-absorbent wall according to the present invention;

FIG. 3 is a cross section of a conduit constructed according to the present invention;

FIG. 4 is a cross section of a second conduit constructed according to the present invention; and

FIG. 5 is a cross section of a third conduit constructed according to this invention.

DESCRIPTION OF A PREFERRED EMBODIMENT

Referring now to the drawings wherein like characters designate identical or corresponding parts, and more particularly to FIG. 1 thereof, a sound-absorbing wall constructed according to the invention is shown having a sheet metal shell 10 and a sound-absorbing acoustic panel or mat 12 spaced therefrom a uniform distance b by spacer webs 14. The sound-absorbing mat 12 may be porous or open pored material, for example, or it may also be fibrous material. It may be compact homogeneous material or it also may be composite material formed of individual strands of sound absorbing material bound or adhering together and providing interstices or dead air spaces between the strands to contribute to the sound absorbing properties of the material. The shell 10 is typically sheet metal as in the usual construction of a fire wall between the passenger and engine compartments of an automobile. Shell 10, however, may be of any other suitable material such as plaster board or plywood as the requirements of different applications dictate. The spacer webs 14 are preferably as few as possible and just enough to hold the acoustic mat 12 in position. The spacer webs 14 may take any known form and are shown schematically for purposes of illustration.

The interspatial dimension b between the inside face 16 of the acoustic mat 12 and the outside face 18 of the shell 10 is selected to coincide with one-quarter of the wave length of the highest frequency to be attenuated. For example, there is little utility in attenuating the frequencies that lie above the normal hearing range of a human being or frequencies which are within the hearing range but, because of the conditions in which the invention is used, are at low amplitudes or are otherwise not objectionable.

The theory which is believed to explain the results achieved by this invention is described below. This theory is offered to further illustrate the construction of the preferred embodiments and should not be construed as a limitation to the appended claims.

Adjacent the non-absorbing shell 10, the acoustic particle velocity normal to the shell is zero so that sound absorbing material placed there, as it is in the prior art, does not contribute to sound absorption. This is because sound absorption is related to the acoustic velocity; the particle velocity at the particular location in the sound wave is attenuated by conversion into heat generated by viscous losses of the moving particles of the sound carrying medium within the capillary pores of the porous material, and by friction losses of the vibrating component parts of the material. Since the acoustic velocity adjacent the non-absorbing shell is zero, there is no contribution at that location to the sound attenuation. Accordingly, acoustic material placed at that location in the sound wave does not contribute to sound attenuation and merely represents wasted weight and expense.

On the other hand, the acoustic velocity is maximum at a distance from the shell 10 equal to one-fourth the wave length of the highest acoustic frequency to be absorbed. At this point, the sound absorption material has the highest efficacy since that is the point of greatest amplitude of the oscillations of the particles in the sound carrying medium.

The improved sound attenuation contributed by this invention is illustrated in FIG. 2 which is a graph of the

relationship between the sound absorption value, measured in percent, and the acoustic frequency, measured in kilohertz for a given material. The curves reproduced have been plotted for a given static air pressure, a given air temperature and mean thickness of the sound-absorbing material.

Examining first the full-line curve which represents the case in which the sound-absorbing material is applied directly on the non-absorbing wall with no intermediate space provided therebetween, i.e., the state of the art, we find a maximum sound absorption degree at a frequency above 4 kHz. If a separation is then introduced between the sound-absorbing material and the wall, measuring, for example, 1.2 cm, the full-line curve is shifted into the curve illustrated by the dotted line. It is obvious that now the maximum of the sound absorption curve is placed between two and 3 kHz.

As a role, however, it is not sufficient to attenuate a single frequency or a very narrow frequency band but rather an acoustic frequency band of a particular width must be absorbed in the material. Whereas the interspatial dimension b between the non-absorbing partition and the sound-absorbing panel serves to determine the highest acoustic frequency attenuated, the thickness of the sound-absorbing panel constitutes a further parameter which may be utilized to determine the acoustic frequency range to be absorbed. In a given application, the acoustic frequency range will be $f_2 - f_1$ wherein f_2 constitutes the highest and f_1 the lowest acoustic frequency to be attenuated. For a given frequency range, the thickness d of the acoustic panel should be

$$d = [c(f_2 - f_1)]/4f_1f_2$$

where c is the sound propagation velocity in the ambient medium. In most cases, the medium present will be air; however, the invention may also be utilized in other fluid mediums having different values of c , in which case the thickness d will change proportionately.

The sound attenuating structure may also be constructed as a conduit wherein the shell forms the outside circumferential casing of the conduit and the mat is disposed coaxially within the shell and spaced from the interior surface thereof to leave an annular interspatial zone of uniform cross sectional width. This annular interspatial zone may be used as the fluid flow zone to convey the fluid which flows in the conduit.

The acoustic mat disposed coaxially in the conduit may take the form of a core 19 of solid cross section, as shown in FIG. 3. In this embodiment, the interspatial zone 24 between the interior surface 20 of the shell 10 and the exterior surface 22 of the acoustic mat forms a free flow zone 24 for conveyance of fluid in the conduit. Placement of the flow zone between the mat and the shell yields the advantage that the cross sectional area of the free flow zone 24 becomes larger than in known attenuation devices wherein the same thickness of the mat is applied directly to the shell. As a result, the velocity of flow and the sound level become lower. Moreover, due to the concentration of the sound-absorbing material in the area of the conduit axis the effective thickness of the material is increased since it serves to absorb sound from both diametrical sides of the conduit and the exterior dimensions of the conduit remain the same while the quantity of material is reduced.

The sound absorbing material 19 may be subdivided axially by transversely extending partitions 23 held to the wall of conduit 10 and by means of webs 14'. The partitions 23 are for the purpose of preventing acoustic propagation within the absorbing material in the direction of the conduit axis and, in order not to adversely effect the free flow section 24, the web 14' is made narrow in the direction of the conduit axis.

As shown in FIG. 4, the acoustic mat may take the form of an annulus 25 coaxially disposed with respect to the shell 10. In this embodiment, the cross sectional thickness d of the panel is defined by the same expression which defines the mat thickness of the sound attenuating wall shown in FIG. 1. In this embodiment the axial zone 26 is used for conveyance of fluids through the conduit while the interspatial zone 24 may be used for fluid conveyance or may be divided into hollow chambers by partitions 23' which also divide the sound absorbing mat 25 into pieces to prevent sound propagation axially through the mat 25. If the interspatial zone 24 is to be used for conveyance of fluid, then the dividers 23 will not extend out to the conduit wall 10 but will extend only through the mat 25 and will be connected to the conduit wall 10 by connecting webs similar to webs 14' in the embodiment of FIG. 3.

As shown in FIG. 5, the mat 19' may extend laterally to contact the conduit 10 on diametrically opposite sides thereof. In this embodiment the cross sectional area available for fluid flow is less than the embodiment of FIG. 3, but the mechanical strength of the arrangement and the simplicity of manufacturing techniques make this a desirable embodiment for some applications.

The embodiments of the invention disclosed herein provide sound attenuating structures which arrange the sound absorbing material to minimize weight, size and cost and make the formerly wasted space available for useful purposes. The quantity of sound absorbing material used in these embodiments is less than that used in prior art structures, yet provides sound absorbing characteristics that are an improvement over the prior art.

Obviously, numerous variations and modifications of the above-described preferred embodiments of the invention may be made in light of this disclosure. It is therefore to be expressly understood that the invention may be practiced otherwise than as specifically described while still remaining within the scope and spirit of the claims appended hereto which define the invention.

I claim

1. A sound attenuating structure, comprising:
a shell;
a mat of sound-absorbing material disposed adjacent and parallel to said shell and spaced therefrom a distance substantially equal to one-fourth of the wave length of the highest frequency to be attenuated; and
means for holding said mat parallel to said shell.
2. A sound attenuating structure, comprising:
a shell;
a mat of sound absorbing material disposed adjacent to said shell and spaced therefrom a distance substantially equal to one-fourth of the wave length of the highest frequency to be attenuated, said mat having a thickness d having a value approximated by the expression:

$$d = [c(f_2 - f_1)]/4f_1f_2$$

where f_2 is the highest acoustic frequency to be attenuated, f_1 is the lowest acoustic frequency to be attenuated, and c is the sound propagation velocity in the ambient medium.

3. A sound attenuating structure, comprising:
 a shell forming the exterior wall of a conduit;
 a mat disposed interiorly of and adjacent to said shell
 and spaced from the interior surface thereof a distance substantially equal to one-fourth of the wavelength of the highest frequency to be attenuated;
 and

means for holding said mat parallel to said shell.

4. A sound attenuating structure as defined in claim 3, wherein said mat forms a solid core filling the axial portion of said conduit, the mat and the interior surface of said shell defining therebetween a fluid flow path.

5. A sound attenuating structure as defined in claim 3, wherein the lateral cross section of said mat comprises an annulus having an outside surface parallel to the inside surface of said shell and an inside surface defining a hollow interior of said mat.

6. A sound attenuating structure as defined in claim 5, wherein said interior surface of said mat defines an axial passage for flow of fluids through said conduit.

7. A sound attenuating structure as defined in claim

6, further comprising means restricting fluid flow in said conduit to said axial passage.

8. A sound attenuating structure as defined in claim 6, wherein:
 the thickness of said mat between said inside mat surface and said outside mat surface has a value approximated by the expression:

$$d = [c(f_2 - f_1)]/4f_1f_2$$

- 10 where f_2 is the highest acoustic frequency to be attenuated, f_1 is the lowest acoustic frequency to be attenuated, and c is the sound propagation velocity in the ambient medium.

9. A sound attenuating structure as defined in claim 15 3, further comprising:

partition means extending transversely through said mat and connected to said shell to divide said mat into successive sound absorption sections and to hold said sections in fixed relationship to said shell.

10. A sound attenuating structure as defined in claim 5, further comprising:

partition means extending through said mat and the annular interspatial zone between said shell and said mat and having means defining a centrally disposed opening to leave said axial passage open for fluid flow.
